UNITED STATES PATENT OFFICE.

ENOCH P. HINCKS, OF BRIDGEPORT, CONNECTICUT.

FOLDING-TOP CARRIAGE.

SPECIFICATION forming part of Letters Patent No. 235,528, dated December 14, 1880.

Application filed November 10, 1880. (No model.)

To all whom it may concern:

Be it known that I, ENOCH P. HINCKS, a citizen of the United States, residing at Bridgeport, Fairfield county, Connecticut, have invented new and useful Improvements in Folding-Top Carriages, of which the following is a specification.

My invention relates to certain new and useful improvements in the construction and arrangement of the spring devices employed in connection with folding-top carriages, such as landaus, as will be hereinafter in detail described.

In the drawings, Figure 1 represents a detail elevation of the front portion of a landau; Fig. 2, a vertical section at xx of Fig. 1; Fig. 3, a view similar to Fig. 2, with the upper portion thrown down; Fig. 4, a detail view of the strap-fastening device; and Fig. 5, a section thereof through the center, showing the mode of securing the bolt and strap in place.

Similar letters indicate like parts in the several figures.

A B represent the stationary and movable parts, respectively, of the frame of the carriage, hinged at C, in the usual manner.

D is a metal plate secured to the portion A at the point indicated in the drawings, and formed with an extension or arm, E, having a hole or eye in its lower end, and to which is secured, by a bolt or rivet, a, a link, F, the lower end of which is bifurcated, as clearly shown at Figs. 4 and 5, and furnished with a screw-bolt, G.

H is a lug secured to the lower or stationary pillar, B, and its upper end is formed substantially like the link F, and provided with screw-bolt I.

The link F and lug H are connected by a

strong flat rubber band, K, which is secured 40 in place by the bolts G I, and by this means it may readily be removed for the purpose of substituting new ones of varying length or strength.

By this construction and arrangement of devices it will be seen that the falling front of the carriage is counterbalanced, and may be opened and closed with great facility.

I have illustrated the devices applied only at one point; but it is obvious that they may 50 be used at more than one or at any desired place.

I am aware that adjustable metallic springs have been arranged within the pillars of folding-top carriages; but in the use of all such devices there is a disagreeable noise attendant with the movement of the springs, and a constant liability of the springs getting out of order and becoming inelastic, and, independent of these objections, all these devices are 60 more or less complicated and expensive, while my improved spring is economic of construction and very readily applied.

What I claim as new, and desire to secure by Letters Patent, is—

In combination with the movable portion A and stationary portion B of a folding-top carriage, the metallic devices D E F H and elastic rubber band K, secured in place by screw-bolts G I, substantially as and for the purpose 70 set forth.

In testimony whereof I have hereunto set my hand in the presence of two subscribing witnesses.

ENOCH P. HINCKS.
